OVERSHOT FOR CONTROLLING WILD WELLS

John E. Eckel, Tulsa, Okla., assignor to Esso Research and Engineering Company, a corporation of Delaware

Application March 24, 1955, Serial No. 496,367

2 Claims. (Cl. 166—95)

The present invention concerns apparatus for closing off a wild petroleum well. More particularly the invention relates to an overshot device that can be lowered into place over a wild well and quickly attached to the casing of the well to seal the same.

With any high pressure producing oil well there is always the danger that the well will get out of control and that the well cannot be closed off with the existing equipment. For example when a well is being drilled or repaired the pressure control equipment may become damaged or broken off, so that the pressure of the well can no longer be confined, resulting in a wild well from which gas and oil will rapidly escape and produce a fire hazard, endanger surrounding property and human life, and cause enormous waste of a valuable natural resource. Equipment heretofore used for bringing such a well under control has required that workmen must get close to the well and manipulate the equipment by hand so that there is an accompanying safety hazard.

It is an object of the present invention to provide equipment that can be lowered into place over a wild well and quickly attached by remote control. In accordance with the present invention an overshot apparatus is provided which will fit over the existing casing of the well and which can be quickly connected and sealed by expansible packing means after which conventional blowout prevention equipment attached to the upper end of the apparatus can be closed to shut off the well and the well then killed in a conventional manner. The apparatus is particularly useful for wells in marine locations.

The nature of the apparatus of this invention will be readily understood when reference is made to the accompanying drawings in which:

Figure 1 is an elevational view partly in section showing the manner in which the device can be attached to well casing;

Figure 2 is an enlarged view of a portion of the apparatus of Figure 1 showing the packing member in its deflated position; and

Figure 3 is an enlarged view, similar to Figure 2, showing the packing member in its inflated condition.

Referring now in particular to Figure 1 the apparatus of this invention is shown in place over the well. The elements of the well that are shown include the surface casing 10 which extends above the surface of a body of water 13 and which is surrounded by a conductor pipe 11. The annulus between the surface casing and the conductor pipe is filled with cement 12, the purpose of the outer conductor pipe and the cement seal being to prevent salt water attack on the surface casing. This is common practice for wells that have been drilled into a lake or gulf.

An inner string of casing 15 is supported within the surface casing by means of a casing head 14. Before the apparatus of this invention can be set in place, it is necessary to remove from the well by means of cable

2

type saws, artillery, powerful cranes or other means the interfering surface fittings such as tubing heads, flow manifolds (commonly known as Christmas trees) and the like. In the well shown in Figure 1 all of these fittings have been removed to reduce the top of the well to an effective overall diameter sufficiently small so that the overshot device of this invention can be lowered into place.

The apparatus itself comprises a cylindrical body 17 the top of which is provided with a flange 18 to which have been attached conventional blind ram blowout preventers 19. A bail 20 fastened to the top of the apparatus enables the apparatus to be supported from a crane so that it can be swung into place over the well and centered by means of lateral winch lines attached to the side brackets 24.

A lining of cement or other suitable material 21 is provided within the cylindrical body over most of its length to absorb the abrasion that will occur from rock particles that are carried up from the well in the stream of escaping oil and gas. Mounted within the lower end of the cylindrical body is an annular expansible packing member 25 having an annular cavity 26 accessible through the inlet port 28 so that the packer can be inflated to provide a fluidtight seal in the annulus between the casing and the cylindrical body after the apparatus has been lowered into place. Attached to the inlet pipe 28 by means of a check valve union 30 is a high pressure hose 31 through which hydraulic pressure may be exerted to inflate the packing member. The purpose of the check valve union is to provide for rapid and easy disconnecting of the high pressure hose after the packer has been set. The check valve will of course be placed in that portion of the union that is connected to the port 28. Such check valve unions are commercially available and hence this element is not shown in detail. To prevent damage to the check valve union there are provided a pair of guard plates 32 positioned above and below the union.

A plurality of reinforcing ribs 34 are imbedded in the material constituting the packer and are pivotally attached to the cylindrical body by means of pins 35. It will be seen from a comparison of Figures 2 and 3 that these reinforcing ribs extend inwardly from the cylindrical body toward the well casing when the packer is inflated. These ribs are distributed about the circumference of the packer and serve to reinforce the packer.

Bonded to a lower portion of the packer are a plurality of circumferentially distributed support bars 37 each of which is pivotally attached to the body 17 by means of pins 39. Pivotally supported to the outer end of each of the bars 37 is one of a set of slips 36 which engage the wall of the casing when the packer is inflated and thereby prevent slippage between the cylindrical body 17 and the casing after the packer has been set. After the slips have been set, downward travel of the support bars 37 is prevented by the upward facing shoulder 40 on the inside of the cylindrical body 17. It may be seen that these slips will hold the overshot in position even if casing head 14 and all other projecting shoulders have been removed from the casing. It is of course usually desirable, however, to take advantage of the extra support provided by such projections, such as the shoulder of the casing head 14 and the projecting plugs 33, when such are present.

After the apparatus has been set over the well and the packer has been inflated to seal the apparatus to the casing the blowout preventers 19 are closed in the usual manner. A suitable line is then connected to valve 23, after which the valve is opened and a conventional dense well killing fluid is pumped into the well through the port 22. After the well has been killed the necessary repairs to the well can be made.

It is to be understood that the embodiment of the invention herein described has been presented by way of example and not of limitation and that modifications thereof are contemplated within the scope of the invention as defined by the appended claims.

What is claimed is:

1. An overshot apparatus for use in shutting off flow from a cased well having casing extending upward out of the well which comprises a cylindrical body adapted to be lowered and fit over the casing, means operable to close off the upper end of said cylindrical body, an expandable packing member fixed to the inner periphery of said cylindrical body adjacent the lower end thereof, a plurality of support bars each pivotally attached at one end to the inner peripheral surface of said cylindrical body and adjacent said packing member, a slip member attached to the opposite end of each support bar and

adapted to engage the outer peripheral surface of said casing upon expansion of said packing member, means for expanding said packer member, and a plurality of reinforcing ribs pivotally attached to said cylindrical body and extending into the body of said packing member.

2. An apparatus as defined by claim 1 including an abrasion resistant lining within said cylindrical body above said packing member.
